CLAIM

The ornamental design for a jug cover, as shown and described.

DESCRIPTION

FIG. 1 is a frontal isometric view of my new jug cover, showing my new design;

FIG. 2 is a rear isometric view thereof; and

FIG. 3 is a front plan view thereof, with a jug shown in broken lines to illustrate environment;

FIG. 4 is a rear plan thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in FIG. 3 depict environmental subject matter that forms no part of the claimed design. All other broken lines depict stitching.

1 Claim, 7 Drawing Sheets(56)
